UNITED STATES PATENT OFFICE.

JOSEPH BALON, OF STAUNTON, ILLINOIS.

BIRD-AEROPLANE.

1,377,384.

Specification of Letters Patent. Patented May 10, 1921.

Application filed August 19, 1920. Serial No. 404,712.

To all whom it may concern:

Be it known that I, JOSEPH BALON, a citizen of the United States, residing at Staunton, in the county of Macoupin and State of Illinois, have invented certain new and useful Improvements in Bird-Aeroplanes, of which the following is a specification, reference being had to the accompanying drawings.

10 This invention relates to improvements in aeroplanes.

An important object of the invention is to provide an aeroplane of the heavy duty type having means whereby the supporting 15 surface afforded by the wings thereof may be variably altered.

A further object of the invention is to provide in an aeroplane a new and novel tail construction, the supporting surface of 20 which may be variably altered.

A still further object of the invention is to provide in a tail construction means whereby certain sections of the tail are presented to the air pressure in such a manner 25 as to depress the rear end of the plane and means for simultaneously reducing the supporting surface afforded by the tail in order to further assist in such depression.

Other objects and advantages of the invention will become apparent throughout 30 the course of the following description:

In the accompanying drawings, wherein is shown a skeleton of an aeroplane constructed in accordance with a preferred embodiment of my invention:

Figure 1 is a side elevation thereof;

Fig. 2 is a plan view thereof;

Fig. 3 is a rear elevation thereof;

Fig. 4 is a section on the line 4—4 of 40 Fig. 1;

Fig. 5 is a section on the line 5—5 of Fig. 1;

Fig. 6 is a detail sectional view showing the operation of the forward elevators;

45 Fig. 7 is a detail sectional view showing the operating mechanism for the wings, and

Fig. 8 is a sectional view taken through the forward plane of the forward elevator.

Referring now more particularly to the 50 drawings, the numerals 10 and 11 indicate supporting axles which support a rectangular lower frame 12 at the ends thereof.

The axle 11 is provided with steering wheels 13, the direction of which is controlled by 55 any suitable steering gear apparatus 14 em-

bodying a wheel 15 positioned adjacent the aviator's seat designated at 16. A rectangular frame 12 has extending upwardly therefrom at the corners thereof supports 17 which support an upper rectangular frame 18. Between the sides of the lower and upper rectangular frames vertical braces 19 are likewise employed.

The numeral 20 indicates transversely curved wings, each provided with spaced, 65 inwardly extending arms 21 which are pivotally mounted upon the upper rectangular frame 18, as indicated at 22, (Fig. 4). The inner adjacent ends of the levers 21 are pivotally connected as by links 23 to the upper 70 end of vertically extending links 24, the lower ends of which are connected to arms 25 of the pivotally mounted bar 26 which extends longitudinally of the lower frame. Adjacent the aviator's seat 16 the longitudinally extending bar 26 is provided with a vertical arm 27, to the free end of which is pivotally connected one end of a worm 28.

This worm extends through a block 29 operated by the hand wheel 30 which block is 80 rotatably mounted in and held against longitudinal movement by a support 31 carried by one of the vertical bracing members 19. To the under surfaces of the planes 20 are pivotally secured link connections 32 85 which are in turn secured to the body of the frame adjacent the lower end thereof. These link connections effectively prevent undue elevation of the corners 20. The planes 20 are provided at their rear or trailing edges 90 with ailerons 33 operable from the aviator's seat in the usual manner, as indicated at 34.

Extending forwardly from the upper frame 18 are braces 35 which are joined by braces 36 extending forwardly from the lower rectangular frame and which support a collar 37 in which is rotatably mounted the drive shaft 38 of tractor propeller 39. At the sides of the frame rotatably mounted in journals 40 carried by the vertical supports 19 are the drive shafts 41 for a pair of auxiliary tractor propellers 42, and rear of the tractor propellers and preferably rear of the aviator's seat drive shafts 43 are mounted which bear auxiliary pusher propellers 44. The main and auxiliary tractor propellers are preferably driven by a battery composed of a plurality of engines evenly distributed in weight about the structure in order that in event of the failure of 110

one engine it will not be necessary to land the machine.

Pivottally mounted intermediate the supports 45 carried by corner members 17 at the forward end of the frame is a transversely extending bar 46 having extending upwardly therefrom and centrally thereof an arm 47 and adjacent the ends thereof relatively shorter arms 48 arranged upon each side of the arm 47. Pivottally connected to the forward edge of the upper rectangular frame, as at 49, is the rear or trailing edge of an elevator plane 50 of a width approximately equal to the combined widths of the body frame and the wings 20. Pivottally connected to the forward edge of the elevator plane 50 is an auxiliary elevator plane 51. Links 52 connect the short arms 48 of the bar 46 and the under surface of the main elevator plane 50 and the link 53 connects the free end of the arm 47 with the under surface of the auxiliary elevator plane 51. To this link 53 is pivottally connected the forward end of an operating arm 54, the rear end of which has swivel connection with a worm 55 provided with an operating hand wheel 56 whereby the operating arm 54 may be drawn toward or moved away from the aviator's seat as desired. Movement of the operating arm toward the aviator's seat causes a simultaneous downward movement of the main and auxiliary elevator planes and because of the difference in lengths of the arms 47 and 48, the auxiliary plane 51 moves at a greater speed than the main elevator plane 50, and accordingly, varies its effective angle with relation thereto, thereby varying the relative camber of these sections and accordingly the lifting power exerted thereby.

A tail is provided composed of substantially rectangular, horizontally disposed supporting sections 57 which have their forward ends spaced and the adjacent portions thereof pivottally connected to the frame, as at 58. The forward edges of these planes are likewise connected with the frame by a link structure 59 which permits of rotation of the supporting sections 57 about the pivots 58. These supporting sections 57 normally diverge rearwardly and each have pivottally connected to the inner or adjacent edges thereof a substantially triangular supporting section 60, the inner or adjacent edges of the triangular sections being pivottally connected, as at 61. An examination of the drawings will show that in event of pivotal movement of the sections 57 so that the rear ends thereof are separated, the section 60 flattens downwardly, increasing the effective supporting area of the tail. Means are provided for moving the section 60 into adjusted position, comprising links 62 engaging the under surface of the section 60 adjacent the pivot point thereof,

said links having their inner ends pivottally secured to the free ends of levers 63 supported by the frame. Means are provided for simultaneously moving the levers 63, consisting of a cross bar 64 (Fig. 2) connecting the levers and to which is connected one end of a link 65 having its opposite end connected to one end of an operating lever 66 positioned adjacent the aviator's seat. It will be seen that by operating the lever 66, the central portions of the tail 60 may be moved upwardly or downwardly as desired, thereby moving the side sections inwardly and decreasing the longitudinal supporting area of the tail. The sections 57 of the tail may be further supported by brace links 67 extending intermediate the frame and the under surfaces of the sections 57 and pivottally connected with the frame. A vertically disposed rudder 68 is provided which is operable through a segment 69 and link 70 by an operating lever 71 positioned adjacent the aviator's seat.

The upper surface of the plane is preferably covered by an arched surface 72 affording a wind tunnel from which the air as it emerges impinges against the faces of the triangular central sections 60 tending to depress the rear end of the machine.

From the foregoing it will be obvious that I have provided a plane wherein the effective supporting area of the wings and tail may be readily altered as desired; and it will likewise be obvious that the construction of the same as hereinbefore set forth is capable of some change without departing from the spirit of my invention. I, accordingly, do not limit myself to the construction as hereinbefore set forth, except as so limited by the subjoined claims.

What I claim is:—

1. In an aeroplane, a body frame, a supporting tail structure connected with the plane and means for adjustably altering the amount of supporting surface afforded by said tail structure embodying a pair of spaced rearwardly diverging supporting surfaces pivottally connected at their forward ends to said frame and a second pair of pivottally connected supporting surfaces having their free ends pivottally connected with the adjacent edges of the supporting surfaces of the first named pair, and means for moving the rear ends of the first named pair toward a common center whereby said pivotal connection of the second named pair is shifted upwardly.

2. In an aeroplane, a body frame, a supporting tail structure connected with the frame and means for adjustably altering the supporting effect of said tail structure, said tail structure embodying a pair of spaced, rearwardly diverging, substantially horizontal supporting surfaces pivottally connected adjacent their inner edges at the

forward ends thereof to said frame, a pair of substantially triangular, pivotally connected supporting surfaces disposed intermediate said first named supporting surfaces and having their outer edges pivotally connected therewith and means for elevating the last named supporting surfaces

at the pivotal connection thereof whereby the rear ends of the first named supporting surfaces shift toward a common center. ¹⁰

In testimony whereof I hereunto affix my signature.

JOSEPH BALON.
